PREFORMED POCKET FOR A GARMENT

Elizabeth L. Watts, Hayward, Calif., assignor to George R. Mirande, Fremont Calif.

Filed Feb. 26, 1970, Ser. No. 21,746

Term of patent 14 years

Int. Cl. D2—08

U.S. Cl. D2—400

FIG. 1

FIG. 2

FIG. 1 is a front elevational view of a preformed pocket for a garment showing my new design;

FIG. 2 is a rear elevational view; and

FIG. 3 is an edge view thereof.

I claim:

The ornamental design for a preformed pocket for a garment, as shown.
